UNITED STATES PATENT OFFICE

GEORGE W. GILDERMAN, OF MISHAWAKA, INDIANA, ASSIGNEE TO DODGE MANUFACTURING CORPORATION, OF MISHAWAKA, INDIANA, A CORPORATION OF DELAWARE

CORE

Original application filed June 4, 1927, Serial No. 196,473. Divided and this application filed April 26, 1928. Serial No. 273,036.

This invention aims to provide an improved core for use in casting a hollow roll with integral end webs or integral end webs and hubs.

5 In the accompanying drawings:

Fig. 1 is a central longitudinal section of a core embodying the invention.

Fig. 2 is a side elevation thereof.

The core shown in the drawings represents 10 one illustrative embodiment of the invention, which in this instance is of a form suitable for a hollow roll casting with end webs embodying a concavo-convex shape and formed with inwardly extending hub portions.

15 In the drawings 10 indicates the core generally, having the cylindrical body portion 10^a, with spaced end portions 10^b. The end portions 10^b are mainly spaced from the body portion 10^a by recesses 10^c, being connected to said body portion however by the hub portions 10^d. The recesses 10^c are extended into the ends of the body portion 10^a as indicated at 10^e to provide resultant recesses at the ends of the roll or roller cast 25 with the use of this core.

Tying or reinforcing rods 11 extend through and between the body portion 10^a and the end portions 10^b, being located in the connecting hub portions 10^d illustrated in 30 Fig. 1.

The core is constructed in any suitable manner, of any suitable material or composition, and is preferably partially dried and baked thereafter to insure rigidity and adhesion, as well as proper shape and dimensions.

35 The end portions 10^b provide for accurate positioning of the core body portion 10^a in a mold with which it is used, suitable recesses in the mold being provided to accommodate the end portions 10^b, which thus in conjunction with the hub portions and the tying rods 11 securely position and hold the body portion 10^a in spaced relation to the surrounding 40 mold during casting. A longitudinal vent passage 10^f is provided through the body of the roll to permit the escape of gases or the like.

45 A notch 10^g is provided in one of the body portions 10^b for coaction with a positioning

lug in the mold with which the core is used, this insuring proper longitudinal positioning of the core.

The inner faces of the end portions 10^b are shaped or formed to coact with the adjacent ends of the body portion 10^a to form the ends of the roller cast therefrom; in other words, the ends of such roll or roller are defined not only by the ends of the core body portion 10^a but by the inner faces of the 55 body portions 10^b, the intervening recesses being of the same cross sectional configuration and arrangement as the end webs or end webs and hubs of the intended roll casting.

60 It will be seen that my invention provides a core on which a hollow roll can be cast with integral end webs or end webs and hubs the molding of which is determined wholly by the core itself, thereby promoting accurate 65 and uniform formation of the roll heads or ends as is desirable for a perfectly balanced roll.

65 The invention contemplates an improvement in the production of hollow cast conveyor rollers and the like by the utilization of cores embodying the invention in the casting of such rollers, which cores may be made in various forms suitable for hollow roll 70 castings with dished or recessed ends or with 75 their end webs formed with axially extending hubs.

75 In making cores of the character described, I mold complementary longitudinal sections or half parts of the intended core in suitable 80 core boxes, and in the molding process I employ in the boxes semi-circular molding members corresponding in shape, arrangement and position to the intended core recesses, 85 said members comprising segmental templates seated in the boxes so as to be capable of rotation about the core axis. After the molding of the core sections about the embedded templates, and striking off or leveling the core material even with the faces of the boxes, the templates are removed by rotating them about the core axis, thus permitting 90 subsequent release of the boxes from the core. The removal of the templates from the boxes 95 may be accomplished, for example, by apply-

ing suitably apertured stripper plates over the open sides of the boxes, the apertures in the stripper plates registering with the ends of the templates, and then rotating the templates by pushing on one end with a suitable drift or tool inserted through one of the stripper plate openings so that the templates will pass out through the other openings. Then, the stripper plates and templates being removed, and a suitable adhesive material being sprinkled over the faces of the core sections to be joined, the core sections are united by bringing the core boxes into proper juxtaposition to hold the core sections accurately in contact face to face, and maintaining such contact until the adhesive binds them together.

A core making method embodying the above practice is more fully described, in connection with apparatus for carrying out the same, in my application Serial No. 196,473, filed June 4, 1927, of which this application is a division; which said method is the subject matter of my divisional application Serial No. 273,037, filed April 26, 1928, while the said apparatus or means employed is the subject matter of said parent application Serial No. 196,473.

What I claim is:

30 1. A core for coring a hollow roll casting, having integral extensions for exteriorly molding the ends of the casting, said extensions joined to the main core body by central coring portions and having molding faces in fixed spaced relation to the ends of said main core body shaped to mold the ends of the casting in dished form, said molding faces and the confronting faces of the ends of the main core body being curved or inclined in the same general direction with reference to a plane at right angles to the core axis.

25 2. A core for coring a hollow roll casting, having integral extensions for exteriorly molding the ends of the casting, said extensions joined to the main core body by hub coring portions and having molding faces in fixed spaced relation to the ends of said main core body, said ends of the main core body having recesses around the hub coring portions extending from the spaces between the said ends and extensions.

30 3. A core for coring a hollow roll casting, having integral extensions for exteriorly molding the ends of the casting, said extensions having molding faces in fixed spaced relation to the ends of the main core body and joined thereto by hub coring portions and the said ends of the main core body being recessed around the hub coring portions.

35 4. A core for use with a surrounding mold for casting a hollow roll with end webs and axially extending hubs, said core comprising a cylindrical main body portion having integral extensions by which it may be supported in the mold, said extensions joined to the

main body by hub coring portions and providing mold faces in fixed spaced relation to the ends of the main body for exteriorly molding the ends of the casting, the spaces separating the main body from the extensions being of the configuration of said webs and hubs.

5 5. A core comprising a cylindrical body of sandy material having annular recesses providing end parts spaced from a main central part, with connecting hub parts of small diameter, and having an axial vent passage and longitudinal reinforcing rods embedded in the material around said vent passage and extending from the main central part through the hub parts into the said end parts.

10 6. A core for coring a hollow roll casting, having integral extensions for exteriorly molding the ends of the casting, said extensions joined to the main core body by central coring portions and having molding faces in fixed spaced relation to the ends of said main core body shaped to mold the ends of the casting in dished form, said molding faces presenting annular bulging surfaces portions of which project axially beyond or overhang other portions nearer the said central portions.

15 7. A core for a roll casting formed with annular recesses providing surfaces in fixed spaced relation for molding end webs embodying a concavo-convex shape, the said recesses being correspondingly shaped.

20 8. A core for a roll casting formed with annular recesses providing surfaces in fixed spaced relation for molding end webs embodying relatively deflected annular portions, the said recesses being of the shape of said webs and the confronting walls of said recesses accordingly embodying annular portions relatively deflected in the same general direction.

25 9. A core for a roll casting formed with annular recesses providing surfaces in fixed spaced relation for molding end webs of the casting, said recesses being formed to provide undercut portions of at least one wall of the recesses.

30 10. A core for a roll casting formed with annular recesses providing surfaces in fixed spaced relation for molding end webs of the casting, the walls of each of said recesses embodying confronting portions inclined in the same general direction with reference to a plane at right angles to the roll axis.

35 11. A core for a roll casting formed with annular recesses providing surfaces in fixed spaced relation for molding end webs of the casting, each of said recesses having a portion of a wall underlying a surrounding wall portion.

In testimony whereof, I have signed my name to this specification.

GEORGE W. GILDERMAN. 130
